UNITED STATES PATENT OFFICE

151,435

DESIGN FOR A DISPLAY STAND OR SIMILAR ARTICLE

Ralph Epstein, New York, N. Y., assignor to Jacques Kreisler Manufacturing Corporation,
North Bergen, N. J.

Application December 13, 1946, Serial No. 135,488

Term of patent 3½ years

(Cl. D80—9)

To all whom it may concern:

Be it known that I, Ralph Epstein, a citizen of the United States of America, residing at Bronx, New York, New York, have invented a new, original, and ornamental Design for a Display Stand or Similar Article, of which the following is a specification, reference being had to the accompanying drawing, forming a part thereof.

Fig. 2 is a left side view thereof.

Fig. 3 is a right side view thereof.

I claim:

The ornamental design for a display stand or similar article, as shown.

RALPH EPSTEIN.
